US0D1107575S

(12) **United States Design Patent** (10) Patent No.: **US D1,107,575 S**
(45) Date of Patent: ** Dec. 30, 2025

(54) **PH TEMPERATURE DETECTOR**

(71) Applicant: **Yangjiang Jinlong Economic and Trade Co., Ltd.**, Yangjiang (CN)

(72) Inventor: **Su Bincan**, Yangjiang (CN)

(**) Term: **15 Years**

(21) Appl. No.: **29/970,228**

(22) Filed: **Oct. 28, 2024**

(30) **Foreign Application Priority Data**

Sep. 3, 2024 (CN) 202430561413.1

(51) **LOC (15) Cl.** **10-04**

(52) **U.S. Cl.**

USPC **D10/81**; D10/78

(58) **Field of Classification Search**

USPC D10/78, 81

CPC G01N 27/4166; G01N 27/4167; G01N

21/80; G01N 31/22; G01N 31/221; G01N

21/78; A61B 5/145; A61B 5/14539

See application file for complete search history.

(57) **CLAIM**

The ornamental design for the PH temperature detector as shown and described.

DESCRIPTION

FIG. 1 is a Top view thereof;

FIG. 2 is a Rear view thereof;

FIG. 3 is a Stereogram;

FIG. 4 is a Bottom view thereof;

FIG. 5 is a Right view thereof;

FIG. 6 is a Main view thereof; and,

FIG. 7 is a Left view thereof.

1 Claim, 7 Drawing Sheets
